UNITED STATES PATENT OFFICE.

MARCUS HALL RHODES, OF COLEMAN, GEORGIA.

ELECTRIC TIME-SWITCH.

1,353,850.

Specification of Letters Patent. Patented Sept. 28, 1920.

Application filed January 17, 1919. Serial No. 271,762.

To all whom it may concern:

Be it known that I, MARCUS HALL RHODES, a citizen of the United States, residing at Coleman, in the county of Randolph and 5 State of Georgia, have invented certain new and useful Improvements in Electric Time-Switches, of which the following is a specification.

This invention relates to electric time switches and more particularly to a switch designed especially for employment in an electric light circuit and constructed to automatically open the circuit at a predetermined period of time subsequent to manual 10 actuation of an element thereof. For one reason or another it is frequently desirable to locate a wall switch at some point in a large room, hall, or corridor more or less remote from an exit door from the room, 15 hall, or corridor, and where a switch is so located and is of the ordinary type, the person actuating the same to extinguish the lights must proceed in the dark from the point of location of the switch to the exit. 20 This is annoying if a number of articles of furniture or pieces of machinery must be passed on the way to the exit, and under some conditions it might be dangerous to proceed in the dark. Therefore the primary 25 object of the present invention is to provide a switch of the wall type which may be actuated in the manner of the ordinary push button switch to immediately close the circuit through the lights but which, when 30 actuated for the purpose of opening the circuit, will be automatically delayed in its operation for a predetermined period of time, thus enabling the person actuating the same to reach the exit before the lights are 35 actually extinguished.

Another object of the invention is to so construct the switch that the means for retarding its automatic operation to break the circuit may be adjusted so as to determine 45 with certainty the period of time which will elapse between manual actuation of the switch, for the purpose of opening or breaking the circuit, and the actual throwing open of the switch.

50 A further object of the invention is to so construct the switch that the retarding thereof may be adjusted so as to provide for instantaneous opening of the switch when actuated for this purpose so that if 55 desired, the lights may be instantaneously

energized and instantaneously extinguished as in the use of the ordinary switch.

The switch embodying the present invention includes in its structure switch mechanism proper including an actuating element 60 and which element is in turn actuated by a trip member adapted to be manually moved in a direction to trip the actuating element to close the switch, means being provided for influencing movement of the trip member in the opposite direction or, in other words, in a direction to trip the actuating element to open the switch, and there being further provided means for retarding the movement of the trip member in the last 65 mentioned direction and a detent member for coaction with the trip member to restrain the same against movement in such direction. The detent member is manually operable to release the trip member, and in 70 this combination of parts the invention contemplates the provision of means providing for a positive release of the trip member upon manual operation of the detent member so that sudden or quick operation of the 75 said detent member and its release for return to normal position cannot result in a reengagement thereof with the detent member to prevent the desired automatic operation of the switch.

85 A further object of the invention is to so construct the switch and particularly the switch mechanism proper and the tripping means therefor that the throwing of the switch blade will be accelerated, thereby 90 providing against arcing, the switch mechanism, so far as concerns the elements thereof which are in the electric circuit, being furthermore wholly independent of the means for tripping the mechanism so that 95 there is no possibility, from this source, of the occurrence of a short circuit.

In the accompanying drawings:

Figure 1 is a perspective view of the time switch embodying the present invention; 100

Fig. 2 is a view partly in side elevation and partly in section illustrating the switch mechanism, one side of the casing being removed;

Fig. 3 is a vertical transverse sectional view on the line 3—3 of Fig. 2;

Fig. 4 is a vertical sectional view on the line 4—4 of Fig. 3, the parts of the switch being shown in the positions assumed when the switch is closed; 110

Fig. 5 is a view similar to Fig. 4 but illustrating the switch parts in the positions which they will occupy when the switch is open;

5 Fig. 6 is a horizontal sectional view taken substantially on the line 6—6 of Fig. 3;

Fig. 7 is a perspective view of the switch proper;

10 Fig. 8 is a perspective view of the detent device.

The mechanism of the switch embodying the present invention is mounted within a suitable casing indicated in general by the numeral 1, this casing being open at its 15 front but provided with a front plate 2 secured in place in any suitable manner permitting of its removal whereby access may be had to the parts of the switch for adjustment or repairs. Ordinarily the casing 20 of the device will be placed in a suitable pocket formed in the wall, the face plate 2 lying flush or substantially flush with the wall surface as is usual in switches of this 25 type, the parts of the switch which are to be manually manipulated being extended through the face plate in position for manipulation as will be presently explained.

The switch proper is illustrated more clearly in Fig. 7 of the drawings and the 30 same consists in part of a base plate 3 of insulating material which is mounted in any suitable manner upon one of the side walls of the casing 1. Spring contact fingers 4 and 5 are secured in any suitable 35 manner upon the said base plate 3 as, for example, at diagonally opposite corners thereof, as shown in the said Fig. 7, and each of these contact fingers is in circuit with a binding post 6 with which may be 40 connected the respective conductor wires (not shown). A stop pin 7 is associated with the contact finger 5 and is designed to limit the movement of the switch blade as will be apparent from an inspection of Fig. 7. 45 This blade is indicated in general by the numeral 8 and the same comprises a substantially circular intermediate portion 9 which is swiveled as at 10 upon the base 3 for turning movement, the blade proper 50 comprising arms 11 and 12 which extend in diametrically opposite directions from the body 9 and are designed to contact with the fingers 4 and 5, respectively, when the blade 8 is turned to the position shown in full 55 lines in Fig. 7, thus bridging the contacts and closing the circuit. When the switch blade is turned, however, to the position shown in dotted lines in the said figure, the arms 11 and 12 will be out of contact with 60 the respective fingers 4 and 5 and the circuit will be broken. Movement of the switch blade to this latter position is limited by means of a stop pin 13 fixed upon the base plate 3 opposite and spaced from 65 the pin 7. The numeral 14 indicates a pin

of insulating material mounted upon the face of the body 9 of the switch blade and which pin is to be engaged by an actuating element in a manner to be presently explained and for the purpose of shifting the 70 blade from one position to the other.

The actuating means for the switch blade is designed to move or throw the switch blade with an accelerated motion as in a snap switch so as to quickly make and break 75 the contact and thereby preventing arcing, and the said actuating means includes two arms 15 and 16 pivotally mounted as at 17 and provided at their pivoted ends with gear segments 18 and 19 respectively, the 80 said gear segments intermeshing and the segment 18 being smaller than the segment 19 so that when the arm 16 is swung about its pivot, the arm 15 will likewise be swung but more rapidly and through a greater arc. 85 A spring 20 is connected at its ends to the outer ends of the arms 15 and 16 and exerts a pull between the said ends. Thus as the 90 arms move in either direction past dead center or a line passing vertically through their pivots, the spring will act to accelerate the movement of the arms. Secured to the outer or lower end of the arm 16 is an actuating element indicated by the 95 numeral 21 and comprising a strip having terminal fingers 22 and 23 designed to alternately engage the pin 14 as the arms 15 and 16 are swung in one direction or the other. These fingers are also designed to be engaged by the trip member of the 100 switch mechanism as will be presently explained, so that the parts being in the positions shown in Fig. 4 for example, and the arms 15 and 16 being caused to swing about their pivots, the finger 23 will be brought, 105 in the accelerated movement of the said arms, into sudden engagement with the pin 14 thereby swinging or rotating the switch blade to the dotted line position shown in Fig. 7, or the full line position shown in 110 Fig. 5. Likewise when the parts are in the position shown in Fig. 5 of the drawings and the arms 15 and 16 are swung in the opposite direction through movement of the trip device as will be presently explained, the finger 22 of the actuating element 21 will be brought sharply into engagement with the pin 14 so as to throw the switch blade 115 to position bridging the contacts 4 and 5, as shown in Fig. 7 and in Fig. 4. At this 120 point it will be understood that due to the fact that the gear segment 18 is of less diameter than the gear segment 19, the arm 16 is required to move through but a relatively short arc in order to bring the arm 125 15 to a position beyond dead center, whereupon the spring 20 will act to complete the movement of the arms in the manner heretofore explained.

The trip device for causing movement of 130

the actuating member 21 includes a plunger 24 having a squared portion 25 fitting slidably through an opening 26 in the face plate 2 of the casing so as to prevent rotation of the plunger. This plunger at its rear or inner end fits slidably through an opening 27 in one end of a dash-pot cylinder 28, and has secured upon it a piston head 29 which works in the said cylinder. 5 A spring 30 preferably in the form of a double spiral whereby it may be compressed to a maximum degree and will, under compression, occupy minimum space, is fitted onto the plunger 24 and bears at one end 10 against the said end of the cylinder 28 and at its other end against a collar 30' which is secured by means of a set screw 31 upon the said plunger. For a purpose to be presently explained, an arm 32 extends laterally from the collar 30' and the lower edge of this arm at the rear side thereof is beveled as indicated by the numeral 33, and the forward side of the arm is formed with an inwardly and upwardly directed bevel 15 34. A push-button or knob 35 is secured to the outer end of the plunger 24 and it will be understood that pressure may be exerted manually in an inward direction against the plunger so as to move the same inwardly 20 against the tension of the spring 30, the piston head 29 being likewise moved inwardly in the cylinder 28. It will be understood at this point that when the plunger is relieved of such pressure the spring will 25 move the same outwardly in expanding, but this movement will be retarded to a greater or less degree by the movement of the piston head in the cylinder and depending upon the rapidity with which air is permitted to 30 enter the cylinder. In order that the admission of air into and the escape of air from the cylinder 28 may be regulated, the cylinder is provided with a vent opening 36 near its rear end and from this opening 35 leads a vent pipe 37. This pipe extends at its forward end to a point opposite an opening 38 in the face plate 2 of the casing. The said end of the pipe is exteriorly threaded, and adjustably fitted thereto is a cap valve 40 comprising a sleeve 39 and a head 40, the sleeve being rotatably fitted through the opening 38 with the head 40 located at the exterior of the casing and immediately in front of the face plate 2. It will be understood, of course, that when the head 40 is rotated so as to tighten the sleeve upon the end of the vent pipe, the entrance of air to the cylinder and the escape of air therefrom is restricted to such a degree that the piston will move but slowly under the influence of the spring 30 so that the movement of the plunger 24 will be greatly retarded. On the other hand when the head 40 is rotated so as to partly unthread the sleeve 39 45 from the pipe, air will be admitted more readily to the cylinder and thus the movement of the plunger will not be so greatly retarded. Therefore by rotatably adjusting the head 40, the speed with which the plunger is returned to projected or normal position under the influence of the spring 30 may be varied to any desired extent. If desired a scale 41 may be arranged upon the face of the plate 2 concentric to the opening 38, and the head 40 may be provided with 50 an indicator pointer 42 for coaction with the scale so that the person adjusting the head 40 may bring the pointer to registration with any desired mark upon the scale indicating the number of seconds or minutes 55 30 which will elapse between release of the plunger 24 and movement thereof to the outward limit under the influence of the spring 30 and under the conditions to be presently recited. As under certain conditions to be 60 presently pointed out it may be desirable to freely admit air to the cylinder so that the outward movement of the plunger will not be retarded but the spring 30 will act immediately to move the same to the outward 65 limit of its movement, the sleeve 39 is formed in its side with an opening 43 through which air may freely pass when the sleeve has been rotated so as to position this 70 opening beyond the end of the vent pipe. 75 In order that the plunger 24 may be restrained against outward movement when once shoved inwardly to close the circuit, a detent member is provided and this member is clearly shown in Fig. 8 of the drawings. 80 The detent member comprises a lever 44 pivotally mounted at one end as at 45 upon the rear wall of the casing 1 and extending at its forward end through a slot 46 formed in the face plate 2 of the casing and provided at its said end with a finger knob 47 preferably having a beveled or flat upper side 48 indicating that the knob is to be depressed for the purpose of actuating the lever. Pivoted as at 49 in a slot 50 formed 85 vertically through the lever 44, is a detent pawl 51. The forward or free end of the pawl 51 is formed to provide a nose 52 having an inclined upper side 53 and provided at its rear end with a shoulder 54 which is inclined slightly rearwardly and which is 90 designed to engage against the bevel 34 of the arm 32 when the plunger 24 is shoved inwardly and the said arm rides over the inclined upper edge 53 of the said nose 52. 95 The pawl 51 is provided below the lever 44 with a lip or shoulder 55 designed to engage the under side of the lever and thus limit the upward swinging movement of the pawl upon its pivot. The under side of 100 the lip 55, indicated by the numeral 56, is inclined downwardly and forwardly, and a leaf spring 57 is secured at an intermediate point to the under side of the lever 44 105 rearwardly of the pivot 49, as indicated by 110 115 120 125 130

the numeral 58, the end portion of this spring forwardly of its point of attachment to the lever 44 bearing against the said under side 56 of the lip 55, and the end 5 portion of the spring at the opposite side of its point of attachment to the said lever being bowed to extend downwardly and bear against the bottom wall of the casing 1. Thus the leaf spring serves to hold the 10 lever 44 bodily swung upwardly upon its pivot, which movement of the lever is limited by the engagement of its forward end portion against the upper end of the slot 46 in the face plate of the casing, and the 15 spring serves the further purpose of yieldably holding the pawl 51 rocked in an upward direction upon its pivot.

In the operation of the switch to close the circuit the plunger 24 is shoved inwardly 20 against the tension of the spring 30 in which movement of the plunger the arm 32 will ride at its bevel 33 over the inclined upper edge 53 of the nose 52 of the pawl 51, thus depressing or swinging the pawl downwardly 25 upon its pivot and until the arm engages behind the shoulder 54 of the said pawl whereupon the plunger will be restrained against outward movement. In the meantime the arm 32 will have engaged 30 the finger 23 of the actuating member 21 and caused this member to move so as to swing the arm 16 and the arm 15 to the position shown in Fig. 4 of the drawings, which movement of the arms is accomplished automatically 35 by the spring 20 as the arms pass dead center, and as this movement of the arms is accelerated, the member 21 will be quickly moved so as to cause the finger 22 to sharply engage the pin 14 and immediately 40 turn or throw the switch blade so that the ends of its arms will contact with the contact fingers 4 and 5. In order to operate the switch so as to break the circuit, it is only necessary to press downwardly upon 45 the finger knob 47. In this movement of the knob, the lever 44 will be swung downwardly carrying with it the pawl 51 and disengaging the shoulder of the pawl from the arm 32. The spring 30 will then act to 50 impart outward travel to the plunger 24 which movement of the plunger is, however, retarded through the compression of air in the dash-pot cylinder 28 and the restricted admission of air to this cylinder. As before 55 pointed out, the cap valve comprising the sleeve 39 and head 40 may be adjusted so as to vary the extent to which the speed of movement of the plunger will be retarded under the influence of the spring. Immediately 60 upon actuation of the lever 44 in the manner above pointed out, the spring 57 will act to rock the pawl 51 upon its pivot 49 so that the shoulder 54 will be immediately carried rearwardly beyond the position occupied by it when in engagement

with the arm 32. Thus if the lever 44 is actuated in a careless manner or even should it be very quickly depressed and immediately released before any appreciable motion of the plunger head takes place, there is no possibility of the shoulder 54 of the pawl 51 reengaging with the arm 32 as the lever 44 is swung upwardly under the influence of the spring 57 and therefore automatic operation of the switch in the manner above pointed out is insured after depression of the said detent lever 44. 70

Having thus described the invention, what is claimed as new is:

1. In an electric time switch, switch mechanism including an actuating element, a trip member for coaction with the said element, means influencing movement of the trip member in a direction to trip the actuating element to open the switch, a detent for restraining the trip member from such movement, and means for retarding such movement of the trip member. 80

2. In an electric time switch, switch mechanism including an actuating element, a trip member for coaction with the said element, means influencing movement of the trip member in a direction to trip the actuating element to open the switch, a detent for restraining the trip member from such movement, and means for retarding such movement of the trip member and adjustable thereby to provide for variation in the period of time which will elapse between the release movement of the detent and the 90 coaction of the trip member with the said actuating element of the switch mechanism. 95

3. In an electric time switch, switch mechanism including an actuating element, a trip member for coaction with the said element, means influencing movement of the trip member in a direction to trip the actuating element to open the switch, means for optionally restraining operation of said trip member, and means for retarding such movement of the trip member. 100 105

4. In an electric time switch, switch mechanism including an actuating element, a trip member for coaction with the said element, a spring influencing movement of the trip member in a direction to trip the actuating element to open the switch, a detent for restraining the trip member from such movement, and dash-pot means for retarding such movement of the trip member. 110 115

5. In an electric time switch, switch mechanism including an actuating element, a trip member for coaction with the said element, a piston plunger by which the trip member is carried, a cylinder in which the piston of the plunger works, means for restricting the entrance of air and its exit from the cylinder, a spring upon the plunger bearing against one end of the cylinder and against a fixed portion of the plunger and influencing 120 125 130

ing movement of the plunger in a direction to trip the actuating element to open the switch, and a detent for restraining the trip member from such movement.

- 5 6. In an electric time switch, switch mechanism including a blade and an actuating element therefor, the blade having an abutment element for engagement by the actuating element, a trip member for coaction with the actuating element to move the same a predetermined distance, means for moving the actuating element a further distance at an accelerated speed, means influencing movement of the trip member in a direction to trip the actuating element to open the switch, and a detent for restraining the trip member from such movement.

- 10 7. In an electric time switch, switch mechanism including a blade and an actuating element therefor, the blade having an abutment element for engagement by the actuating element, a trip member for coaction with the actuating element to move the same a predetermined distance, means for moving the actuating element a further distance at an accelerated speed, means influencing movement of the trip member in a direction to trip the actuating element to open the switch, a detent for restraining the trip member from such movement, and means for retarding such movement of the trip member.

- 15 8. In an electric time switch, switch mechanism including a blade, arms mounted for swinging movement and having intermeshing gear segments, a spring extending between the free ends of the arms, an actuating element carried by one of the arms and having terminal portions, a pin upon the switch blade engageable by the terminal portions of the actuating element, a trip member movably mounted and arranged for coaction with the said terminal portions of the actuating element, means influencing movement of the trip member in a direction to trip the actuating element to open the switch, a detent for restraining the trip member from such movement, and means for retarding such movement of the trip member.

- 20 9. In an electric time switch, switch mech-

anism including a blade, arms mounted for swinging movement and having intermeshing gear segments, the gear segments of the arms being so relatively proportioned as to provide for more rapid movement of one arm and through a greater arc than the other arm, a spring extending between the free ends of the arms, an actuating element carried by one of the arms and having terminal portions, a pin upon the switch blade engageable by the terminal portions of the actuating element, a trip member movably mounted and arranged for coaction with the said terminal portions of the actuating element, means influencing movement of the trip member in a direction to trip the actuating element to open the switch, a detent for restraining the trip member from such movement, and means for retarding such movement of the trip member.

25 10. In an electric time switch, switch mechanism including an actuating element, a trip member for coaction with the said element, means influencing movement of the trip member in a direction to trip the actuating element to open the switch, the trip member having an arm, a pivoted manually operable lever, a pawl carried by the lever, and a spring yieldably holding the lever rocked to position with the pawl in the path of movement of the arm of the trip member.

30 11. In an electric time switch, switch mechanism including an actuating element, a trip member for coaction with the said element, means influencing movement of the trip member in a direction to trip the actuating element to open the switch, the trip member having an arm, a pivoted manually operable lever, a pawl carried by the lever, and a spring yieldably holding the lever rocked to position with the pawl in the path of movement of the arm of the trip member, the said pawl being pivotally mounted upon the lever and the said spring serving also to yieldably hold the pawl rocked to the limit of its movement in a direction to engage with the arm of the trip member.

35 In testimony whereof I affix my signature. 100

MARCUS HALL RHODES. [L.S.]
